John Vaudreuil
By R. S. Caldwell
ATTORNEY

UNITED STATES PATENT OFFICE.

JOHN VAUDREUIL, OF MILWAUKEE, WISCONSIN.

DISHBASKET.

Application filed July 27, 1921. Serial No. 487,907.

To all whom it may concern:

Be it known that I, JOHN VAUDREUIL, a citizen of the United States, and resident of Milwaukee, in the county of Milwaukee and State of Wisconsin, have invented new and useful Improvements in Dishbaskets, of which the following is a description, reference being had to the accompanying drawings, which are a part of this specification.

10 The invention relates to dish baskets.

The object of the invention is to provide a dish basket into which the dishes, such as cups, saucers, glasses and plates, may be stacked either for washing or rinsing or drying, without danger of injury to the dishes, the basket including a metal frame provided with wooden buffers.

20 A further object of the invention is to provide a simple and effective connection between the sides of the basket and the wooden rack rods which will permit of ready replacement of these rods.

25 The invention further consists in the several features hereinafter set forth and more particularly defined by claims at the conclusion hereof.

30 In the drawings: Fig. 1 is a side view of a device embodying the invention; Fig. 2 is a plan view thereof, parts being broken away; Fig. 3 is a perspective view of a rack rod connection.

A skeleton frame is formed of relatively heavy wire frames 4 joined together by upright wire rods 5 welded or otherwise suitably secured to the frames 4. At the corners reinforcement wires 6 are welded to the rods 5, and other wires 7 are welded to intermediate rods 5 to brace them. This construction provides a strong wire basket, but as there is danger of cracking or breaking dishes in an all-wire basket, wooden buffer rods 8 are connected to the sides by running the rods 5 through spaced holes in these rods 8. The transverse wooden rods 9 form the bottom of the basket and they are also anchored to the frame by having rods 5 pass through their ends. The top buffer rods 8 are held against accidental displacement by means of retainer wires 10 welded to the tops of some of the rods 5 which extend through the top wooden rods.

55 Racks or compartments in the basket are formed by wooden rack bars 11, which may be arranged in pairs or singly to accommodate the dishes. These rack bars extend across the basket and the ends of each bar

are secured to the skeleton frame by means of connectors 12.

Each connector has a closed end 13 and a tubular portion 14 having diametrically disposed slots 15. The slots 15 permit the connectors being slipped over the upright rods 5 to receive the ends of the bars 11 in their tubular portions 14 and thus connect said bars to the wire frame. When the tubular portion 14 has a snug fit with the end of the bar 11, as this bar swells up when wet, the parts will be firmly secured together, but in addition a small screw or nail 16 passed through a hole 17 in the connector and into the end of the bar may be used. In case a rack bar breaks it can be very easily replaced with this form of connection.

As shown in Fig. 1 the connectors are preferably secured to the rods 5 between longitudinally extending parts of the basket, as between one of the wires 7 and one of the buffer rods 8, or between one of the wires 7 and the corner wire 6 to hold the rack bars in position.

80 From the foregoing description it will be noted that the basket is of light but strong construction, may be easily cleaned, prevents injury to the dishes, and those parts most subject to breakage may be readily replaced.

What I claim as my invention is:

1. In a dish basket, the combination of a wire skeleton frame including upright wire rods, wooden buffer rods secured to said upright rods, spaced wooden bottom bars secured to said frame, and a plurality of rack bars secured to said upright rods.

2. In a dish basket, the combination of a wire skeleton frame including upright wire rods, a plurality of rack bars, connectors securing the ends of said rack bars to said rods, each connector having a portion fitting over the end of the bar and slotted to receive the rod between the ends of the slots and the end of the bar.

3. In a dish basket, the combination of a wire skeleton frame including upright wire rods, a plurality of wooden rack bars, metal caps fitting over the ends of said bars and having slots to receive the wire rods between the ends of the slots and the end of the bar.

In testimony whereof, I affix my signature:

JOHN VAUDREUIL.
